UNITED STATES PATENT OFFICE.

JOHN A. RUSSELL, OF CHICAGO HEIGHTS, ILLINOIS. ASSIGNOR OF ONE-HALF TO HENRY BADENIUS, OF CHICAGO HEIGHTS, ILLINOIS.

FLUE-BLOWER

1,010,523.

Specification of Letters Patent.

Patented Dec. 5, 1911.

Application filed June 14, 1911. Serial No. 633,185.

To all whom it may concern:

Be it known that I, JOHN A. RUSSELL, a citizen of the United States, residing at Chicago Heights, in the county of Cook and State of Illinois, have invented certain new and useful Improvements in Flue-Blowers, of which the following is a specification.

My present invention relates to devices known as flue blowers for injecting steam into and through boiler tubes in order to remove soot and other solid products of combustion from the tubes, my object being to provide a device embodying a movable part carrying a jetting head, so constructed and arranged that they may be rotated and moved into, and retracted from, the rear part of the combustion chamber, by means of the steam.

With this in mind my invention resides in the features of construction, arrangement and operation to be hereinafter described with reference to the accompanying drawing, in which—

Figure 1 is a partial vertical section through the rear portion of a boiler furnace, showing my improved device applied thereto. Fig. 2 is a front elevation of the jetting head carried by the moving piston, and Fig. 3 is a transverse section through the device taken on the line 3—3 of Fig. 1.

Referring now to these figures, A indicates the rear portion of a boiler, showing the flues *a*, between which and the rear wall B of the furnace is the rear portion C of the combustion chamber, the rear wall B having a transverse bore at the inner end of which is an enlarged cavity *b*.

As shown, my improved device comprises a main steam pipe 5 which is coupled to the outer end of a cylindrical casing 6 fixed in an opening in the wall B, the inner end of said casing 6 being provided with an internal collar 6^a. Mounted within the casing 6 is a piston 7, of tubular construction, the periphery of which slidably and rotatably interfits the inner surface of the casing collar 6^a, and on the inner end of which is an internal collar 8 which slidably and rotatably interfits the casing bore. A chamber 9 is thus formed between the outer periphery of the piston 7 and the inner periphery of the casing 6, and extending between the collars 8 and 6^a respectively there-

of. Upon the opposite end of the piston 7 is secured the jetting head 10 which is provided with curved and radially extending steam openings 11, the inner ends of which openings communicate with the piston bore, and the formation of which is such that when steam is admitted within the inner open end of the piston, the passage of the steam through the head openings 11 causes rotation of said head and piston. At the same time the admission of steam causes sliding movement of the piston with respect to the casing 6 in order to project the same within the rear portion C of the combustion chamber with its head 10 adjacent to the rear end A of the boiler. The admission of steam through the main pipe 5 is controlled by its valve 12, this valve being opened in order to effect rotation of the piston on its longitudinal axis, when in its inner position, whereby to inject steam through each of the boiler tubes *a*.

Extending from the main steam pipe 5 at a point beyond its valve 12, is a branch pipe 13, which follows along the outside of casing 6 and has its opposite end let into said casing adjacent to its collar 6^a. Thus when the flues have been sufficiently cleaned the main steam pipe valve 12 is closed, and the valve 14 of the branch pipe 13 is opened in order to deliver steam into the chamber 9 around the piston 7 and against the collar 8 of the piston 7 whereby to slide the piston within the casing 6 until the head 10 is within the wall cavity *b* and out of the rear portion of the combustion chamber. The pipe 13 may also be provided with an oil cup 15 in order to deliver a supply of oil within the casing 6 each time the piston is moved.

From the foregoing it will be readily apparent that I accomplish sliding and rotary movement of the piston by means which are at the same time simple and of such nature as to be unaffected by the intense heat of the combustion chamber, to which they are subjected.

I claim:

The combination of a tubular casing having an internal collar adjacent to one end, a hollow piston slidably interfitting the said collar and extending within the casing, said piston being provided with an open inner end and a collar surrounding the same and interfitting the casing, an enlarged head car-

ried by the opposite end of the piston, having outlet openings extending therethrough and communicating with the piston bore, a fluid-pressure supply pipe coupled to the opposite 5 end of the casing, and a branch pipe extending from said supply pipe and into the casing at a point between its collar and the said piston collar, said branch pipe being provided with a valve and said supply pipe be-

ing provided with a valve between the casing and the said branch pipe.

In testimony whereof I affix my signature in presence of two witnesses.

JOHN A. RUSSELL.
